[57] ABSTRACT

An apparatus for increasing the force exerted by a hydraulic press. A pair of headers are mounted on the upper platen of the press and rods extend downwardly from each header and carry blocks that are adapted to be received within pockets in the lower platen. When the upper platen is lowered toward the lower platen and the cooperating dies carried by the platens engage the workpiece, the blocks are automatically locked within the pockets to integrally connect the headers to the lower platen. Auxiliary cylinders mounted on the upper platen exert an upward force against the headers forcing the headers upwardly and thereby increasing the force applied to the workpiece.

HYDRAULIC PRESS

BACKGROUND OF THE INVENTION

The capacity of a hydraulic press is limited by the size of the hydraulic cylinder, the horse power of the motor, the pump size, and the strength of the structural components such as the tie rods. Recently, in the molding of plastic articles, there has been increased emphasis on the use of higher pressures, and modification of an existing press to achieve higher pressures is a costly operation. A modification to obtain higher capacities may require the use of a larger cylinder which in turn may necessitate the use of a larger motor and pump as well as stronger structural components. The result is that in many cases, the cost of modifying an existing press to achieve a higher capacity may be nearly equal to the cost of a new high capacity press. Thus, modifications of a press to obtain higher capacities is, in most cases, not economically practical.

SUMMARY OF THE INVENTION

The invention relates to an inexpensive attachment for an existing hydraulic press for increasing the force exerted by the press without the necessity of increasing the cylinder size, the horse power of the motor, or the pump size. According to the invention, a pair of headers are mounted on the upper platen of the press and rods extend downwardly from each header and carry blocks or shoes which are adapted to be received within pockets in the lower platen. When the upper platen is lowered toward the lower platen and the cooperating dies carried by the platens are brought into engagement with the workpiece, the blocks are automatically locked within the pockets to integrally connect the headers to the lower platen.

With the blocks locked in the pockets, auxilliary cylinders mounted on the upper platen are actuated which exert an upward force against the headers, thereby forcing the headers upwardly and increasing the force applied to the workpiece.

The construction of the invention enables the tonnage or force exerted by a standard hydraulic press to be substantially increased without increasing the size of the hydraulic cylinder, the horse power of the motor, the pump size, or the size of the tie rods. The system of the invention can be selectively operated, meaning that the existing press can be operated, if desired, without the auxilliary system, or the existing press can be utilized in combination with the auxilliary system.

The construction of the invention can be installed with existing hydraulic presses at low cost, or alternately can be combined with new press constructions.

Other objects and advantages will appear in the course of the following description.

DESCRIPTION OF THE DRAWINGS

FIG. 1 is a perspective view of a standard hydraulic press incorporating the auxilliary system of the invention with the press in the partially open position;

FIG. 2 is an end view of the press with the upper platen in the raised position; and

FIG. 3 is a view similar to FIG. 2 showing the upper platen in the lowered position and the auxilliary cylinders operating to increase the force exerted between the platens.

DESCRIPTION OF THE PREFERRED EMBODIMENT

The drawings illustrate a typical hydraulic press including a lower platen 1 and an upper platen 2. The upper platen is moved toward and away from the lower platen by means of hydraulic cylinders 3, and the upper platen is guided in vertical movement by a series of vertical guide rods 4 that extend upwardly from the lower platen.

Suitable dies are mounted on the upper and lower platen, respectively, and as the upper platen is lowered toward the lower platen 1 a workpiece will be engaged by the mating dies in a conventional manner.

According to the invention, a pair of generally box-shaped headers 5 are mounted at the opposite ends of the upper platen 2. When the upper platen 2 is in the upper or raised position, the ends of the header 5 rest on vertical plates 6 that are supported on a horizontal plate 7 carried by the longitudinal stringers 8 of upper platen 2. Suitable web plates 9 are secured to the lower portion of the plate 7 to provide adequate reinforcement.

Each of the headers 5 is provided with a pair of side walls 10 which are joined together at their ends by an end wall 11. A pair of generally rectangular blocks or shoes 12 are located within the interior of each header 5, and rods 13 are threaded within openings in the blocks 12 and extend downwardly through the plate 7.

To secure the blocks 12 to the header 5, each block is formed with a hole 15, while the side walls 10 of the header are provided with two sets of vertically disposed holes 16. A pin 17 is inserted through one set of the aligned holes 16, as well as through the hole 15 to lock the block 12 to the header 5. The use of the pair of holes 16 in each side wall 10 provides a degree of adjustment for the position of the block 12. By inserting the pin 17 through the uppermost holes 16, the block will be positioned in an upper position, while utilizing the lowermost holes 16 will result in the block 12 being located in a lower position.

Each of the rods 13 extends through a bushing 18 mounted on the base plate 7 and the lower end of the rod is threaded within an opening in a shoe or block 19.

When the upper platen is in the fully raised position the shoes 19 will be located a substantial distance above the lower platen and as the upper platen is lowered the shoes 19 will be received within recesses or pockets 20 formed in housings 21 secured to the lower platen 1. As best shown in FIG. 2, each of the housings 21 is generally rectangular in shape having four side walls 22 and a bottom 23 which is welded to the lower portions of the side walls.

The shoes 19 are adapted to be locked within the recesses 20 in housings 21 by locking pins 24 each of which is carried by ram or piston rod 25 that is slidable within a cylinder 26. The cylinders 26 at each end of the press are supported from a mounting bracket 27 attached to the lower surface of base plate 28 of the lower platen 1.

Walls 22 are provided with aligned openings 29 and each shoe 19 is formed with an elongated opening 30 that is adapted to register with openings 29 when the shoe is received within the pocket 20. By extending the piston rods 25, the pins 24 will be inserted in the aligned openings 29 and 30 to lock shoes 19 within the pockets 20. Thus, with the pins 24 in the locked posi-

tion, as shown in FIG. 3, the rod 13 and headers 5 will be integrally connected to the lower platen 1.

A pair of auxilliary hydraulic cylinders 31 are mounted on the plate 7 between the rods 13. The ram of piston rod 32 of each cylinder is threaded within the opening in a block 33 which is secured within the header 5 in the same manner that the blocks 12 are secured to the header. More specifically, each block 33 is provided with an opening 34 that can be brought into registry with one of two sets of aligned openings 35 in the side wall 10 of the header. A pin 36 is adapted to be inserted within the aligned openings 34 and 35 to lock the block 33 with respect to the header 5.

When the press is open and the upper platen is in the raised position, the headers 5 will be supported on the upper edges of the vertical plate 6 and the shoes 19 will be located a substantial distance above the housing 21. As the upper platen 2 is lowered toward the lower platen 17 and the dies carried by the platens are brought into mating engagement, the shoes 19 will be received within the recesses 20, and when the holes 29 and 30 are in alignment, a limit switch is actuated to operate the cylinders 26 and force the locking pins 24 outwardly into the aligned openings 29 and 30, thereby locking the shoes 19, rods 13 and headers 5 to the lower platen.

With the headers 5 integrally secured to the lower platen 1, the auxilliary cylinders 31 are then actuated forcing the rams 32 upwardly against the headers 5, causing the headers to move upwardly with respect to the plate 6. As the headers 5 are integrally connected to the lower platen, this produces an increased force between the platens 1 and 2.

After the pressing operation is completed, the fluid pressure to the cylinders 3 is reversed which acts to raise the upper platen. On initial upward movement of the upper platen 2, the cylinders 26 are actuated to release the locking pins 24. The initial upward movement of the platen 2 serves to remove the weight from the pins 24 so that they can be more easily withdrawn from the aligned holes 29 and 30. After the locking pins 24 are released, the bottom of the shoes 19 react against the bottom wall 23 of housing 21 to increase the stripping force to part the dies. After stripping, the hydraulic pressure to the auxilliary cylinders 31 is released so that the headers 5 will move downwardly by gravity until they are again supported on the upper edge of the plates 6.

The construction of the invention provides a substantial increase in tonnage or force so that the force exerted by a press may be increased two or three fold. The increased tonnage can be achieved without an increase in horse power, pump size or size of the main tie rods.

Due to the use of the blocks 12 and 33, along with the vertically spaced openings in the headers 5, a degree of adjustment is achieved so that the unit can be utilized for various sized dies.

Various modes of carrying out the invention are contemplated as being within the scope of the following claims particularly pointing out and distinctly claiming the subject matter which is regarded as the invention.

I claim:

1. In a hydraulic press construction, an upper platen, a lower platen, means for moving the upper platen toward and away from said lower platen, connecting means having one end connected to one of said platens

and extending in a direction toward the other platen with the opposite end of said connecting means projecting beyond said other platen, abutment means secured to the projecting end of said connecting means and movably mounted with respect to said other platen, and means reacting between said abutment means and said other platen for moving the abutment means in a direction away from said other platen to thereby increase the force exerted between said upper and lower platen.

10 2. The construction of claim 1, wherein said means for moving the abutment means is a hydraulic cylinder unit.

15 3. The construction of claim 1, wherein said connecting means comprises a plurality of rods with one end of each rod connected to said first named platen, said rods extending through openings in said other platen and the opposite ends of said rods being connected to said abutment means.

20 4. The construction of claim 3, and including guide means separate from said rods for guiding the upper platen in movement toward and away from said lower platen.

25 5. In a hydraulic press construction, an upper platen, a lower platen, means for moving the upper platen toward and away from said lower platen to provide a pressing force on a workpiece disposed between said platens, a header disposed above the upper platen and movably mounted with respect to said upper platen, a series of rods, the upper end of each rod being secured to said header, locking means for removably connecting the lower end of each rod to the lower platen, and hydraulic means reacting between the upper platen and said header for moving said header upwardly in a direction away from said upper platen when said rods are secured to said lower platen to thereby increase the pressing force exerted between said platens.

30 6. The press construction of claim 5, wherein each rod is mounted for sliding movement within an opening in said upper platen.

35 7. The press construction of claim 5 in which the upper end of each rod is adjustably connected to the header.

40 8. The press construction of claim 5, wherein the lower platen is provided with a plurality of pockets and the lower end of each rod carries a shoe disposed to be received in a pocket as the upper platen is lowered toward said lower platen, said locking means comprising a pin disposed to be inserted within aligned openings in said pocket and said shoe to thereby secure the rod to said lower platen.

45 9. The press construction of claim 8, and including second hydraulic means operably connected to each pin for moving the pin into locking engagement and for releasing the pin from locking engagement.

50 10. The press construction of claim 8, wherein each pocket is bordered by a bottom wall, said shoes reacting against said bottom walls after withdrawal of said locking pins to aid in separation of the platens.

55 11. The press construction of claim 5, wherein said hydraulic means includes a cylinder mounted on the upper platen and a ram slidably within the cylinder and reacting against said header.

60 12. The press construction of claim 11, and including a block secured to the ram, and means for securing said block to said header.

65 13. The press construction of claim 5, and including guide means separate from said rods for guiding the upper platen in movement with respect to the lower platen.
